US0D1078235S

(12) **United States Design Patent** (10) **Patent No.:** **US D1,078,235 S**
(45) **Date of Patent:** **** Jun. 10, 2025**

(54) **BOOT**

(71) Applicant: **ROTHY'S, INC.**, San Francisco, CA (US)

(72) Inventor: **William Roth Martin**, San Francisco, CA (US)

(73) Assignee: **ROTHY'S, INC.**, San Francisco, CA (US)

(**) Term: **15 Years**

(21) Appl. No.: **29/942,126**

(22) Filed: **May 14, 2024**

1,979,391 A 11/1934 Laybolt

(57) **CLAIM**

The ornamental design for a boot as shown and described.

DESCRIPTION

FIG. 1 is a front right perspective view of a boot showing my new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The even-dashed broken lines shown in the figures are included for the purpose of illustrating environmental structure of the boot that forms no part of the claimed design. The dot-dashed broken lines shown in the figures are included for the purpose of illustrating the claim boundaries and form no part of the claimed design.

1 Claim, 7 Drawing Sheets
